[57] CLAIM

The ornamental design for a transfer tape holder, as shown and described.

DESCRIPTION

FIG. 1 is a plan view of a transfer tape holder showing our

new design;

FIG. 2 is a front view thereof;

FIG. 3 is a bottom view thereof;

FIG. 4 is a left side view thereof;

FIG. 5 is a right side view thereof;

FIG. 6 is a rear view thereof;

FIG. 7 is a view showing the opened holder with the cover (or cap) member removed for convenience of illustration;

FIG. 8 is a perspective view of FIG. 1;

FIG. 9 is a plan view of the holder body with the cover (or cap) member removed for convenience of illustration;

FIG. 10 is a front view of the holder body with the cover (or cap) member removed for convenience of illustration;

FIG. 11 is a bottom view of the holder body with the cover (or cap) member removed for convenience of illustration;

FIG. 12 is a rear view of the holder body with the cover (or cap) member removed for convenience of illustration;

FIG. 13 is a left side view of the holder body with the cover (or cap) member removed for convenience of illustration;

FIG. 14 is a right side view of the holder body with the cover (or cap) member removed for convenience of illustration;

FIG. 15 is a front view of the cover (or cap) member with the holder body removed for convenience of illustration;

FIG. 16 is a left side view of the cover (or cap) member with the holder body removed for convenience of illustration;

FIG. 17 is a right side view of the cover (or cap) member with the holder body removed for convenience of illustration; and,

FIG. 18 is a plan view of the cover (or cap) member with the holder body removed for convenience of illustration.
